UNITED STATES PATENT OFFICE.

ISAAC PATRICK, OF JAMAICA, NEW YORK.

COMPOSITE BLADE FOR SCISSORS, SHEARS, ETC., AND CUTTER THEREFOR.

Application filed April 16, 1925. Serial No. 23,506.

This invention relates to composite blades for scissors, shears and the like, one part of which is a detachable cutter and is replaceable by another when the edge thereof becomes dull, and also to a cutter, and aims to provide improvements therein.

The invention provides composite blades for scissors or shears of an improved construction whereby a secure connection between the parts of said blade is obtained. The improved construction is simple and well suited for large scale manufacture.

The invention provides a cutter or cutting part, which, with the parts of the fastening means formed thereon, is readily made from a flat strip of metal.

Certain preferred embodiments of the invention are illustrated in the accompanying drawings, wherein

Figure 1 is a side view of the scissors or shears opened as in cutting, provided with the improved composite blade.

Fig. 2 is an enlarged edge view of the scissors with parts thereof, shown in section.

Fig. 3 is a transverse section taken on the plane of the line 3—3 of Fig. 2.

Fig. 4 is a transverse section taken on the plane of the line 4—4 of Fig. 2.

Fig. 5 is an edge view of the cutter element.

Fig. 6 is a top plan view of the cutter element.

Figs. 7, 8 and 9 are detail views of a modification of the cutter blade shown in the preceding figures.

Referring first to Figs. 1 to 6 of the drawings, numerals 10, 11 indicate a pair of blades having handles 12, 13 forming a scissors, the blades of which are pivoted, as indicated at 15, and said blades being adapted to be opened and closed by the opening and closing of the handles 12, 13 in the usual and well understood manner. One or both of the blades 10, 11 is a composite blade, and as herein shown, both of said blades are of this type. The composite blade comprises a cutter or cutting portion 17 and a supporting portion 18.

The cutter 17 is preferably in the form of a thin flat strip of metal having a sharpened edge 20 thereon constituting a cutting edge. The supporting portion 18 on its inner face is provided with a shallow recess 22 in which the cutter 17 is adapted to be fit or lie and be fastened. The said supporting portion 18 at

the lower part or to the rear of the recess 22 opposite the cutting edge 20 (when said cutter is in said recess) is preferably provided with a shoulder 25 adapted to firmly support the said cutter 17 under the pressure exerted on the cutting edge 20 in the act of cutting.

Means are provided for fastening the cutter 17 and the portion 18 together, and preferably these means are provided at or near the two ends of the cutter. These means are of such a character that the cutter 17 is substantially flat and is very well suited to manufacture, packing and use.

The fastening means 30 at the inner end of the cutter 17 is conveniently a prolongation 31 of the flat recess 22 to or near the pivot 32 of the scissors. The cutter 17 is conveniently provided with a tongue 33 projecting longitudinally thereof in the plane of the faces of the flat sides adapted to fit in the prolonged portion 31 of the recess 22. The supporting portion 18 is provided with means for holding the inner end of the cutter 17 against the shoulder 25 thereon, and this means is conveniently a shoulder 34 opposite the shoulder 25, the shoulders 34 and 25 being spaced the width of the tongue 33 of the cutter 17, the part 31 of the recess is at a part of the scissors which is normally covered, or partly covered by the opposite blade during the normal use of the scissors in cutting, and the opposite blade serves to hold the cutter 17 against the broad face of the recess 22.

The two blades 10, 11 are preferably resiliently drawn together at the pivotal connection, and to this end, said connection is conveniently in the form of a hollow rivet 32 having a head 36, and its opposite end 37 turned over and confining between said ends and the blades one or more spring washers 38. The parts of the scissors as thus far described are substantially those as described in my applications Ser. No. 742,829, filed October 10, 1924, and Ser. No. 23,505, filed April 16, 1925.

The main feature of novelty of the present invention resides in the means at the outer end of the cutter for fastening it to the supporting part. As herein shown, these means conveniently comprise a tongue and groove connection, the tongue or tongues 40 being formed integrally with the cutter 17, and preferably extending in a direction longi-

tudinally with respect to the cutter. Said tongues 40 are also preferably so formed that a portion thereof 41 lies within the planes of the faces of the cutter 17 and with parts 42 disposed in planes inclined to the planes of the faces of the cutter and preferably in planes inclined to the longitudinal dimension of the cutter. It is desirable that the tongues are resilient, and notwithstanding that they are formed from the metal of the blade of the cutter which is preferably of high quality spring steel, additional resiliency is provided for them by cutting openings 43 at the juncture of said tongues with the body of the cutter 17. To receive these tongues, the supporting part 18 is formed with a recess 45 at the inner face thereof adjacent the rear edge of the supporting part to a depth corresponding to the thickness of the cutter 17, and of a length substantially equal to that of the portion 41 of the tongues 40. And communicating with said recess 45 are the inclined recesses 46 cut in the rear edge of the supporting member 18, and adapted to receive the angular portions 42 of the tongues 40.

In the modification shown in Figs. 7, 8 and 9, the tongues 40' are formed with a portion 41' similarly disposed with respect to the cutter, as is the part 41 with respect to the cutter 17, but the inclined portions 42', it will be noted, have a much less degree of inclination with respect to the planes of the cutter than those shown in the preceding figures. Also, instead of inclined recesses to receive the portions 42', the rear edge of the supporting part 18 is formed with a recess or groove 46' in its rear side, the faces of which extend substantially parallel to the inner face of the supporting part 18, and therefore, parallel to the planes of the faces of the cutter 17, and the width of said recess is substantially equal to the thickness of the cutter 17 or tongues 42'. When a cutter is fastened to a support through the medium of means such as hereinbefore described as positioned at the outer end of the blade, it will be appreciated that because of the resiliency of the tongues and the tendency of the inclined parts thereof to assume their original or flat position of the blade from which they are formed, that said fastening means will tend to cause the cutter 17 to lie flat within the recess 22 in the supporting part. To further insure the proper engagement and alignment of the cutter 17 on the support 18 and to resist canting or twisting of the cutter in the recess 22, the cutter may be provided with one or more ribs 50, 51 projecting from its back face and adapted to fit into corresponding recesses or depressions 52, 53 formed in the supporting part 18 of the blade, the ribs and slots being preferably formed with parallel walls. The formations

of the ribs and slots with parallel walls is conducive to manufacture with great accuracy.

The cutter 17 may be formed of flat sheet metal and may be given a very hard temper which enables a cutting edge to be provided which is more durable than the ordinary one piece blades. Moreover, with the type of scissors herein described, the adjustment of the cutting blades does not get out of order since the two cutting edges, even when one cutter 17 is substituted for another, always maintain their proper relation or (tension).

When a cutter 17 becomes dull it may be replaced by another, the parts of the fastening means at the outer end of the scissors being forced or sprung apart by the insertion of a sharp instrument between the cutter and its support, and the inner end 33 of the cutter slid outwardly out of the portion 31 of the recess 22. The new cutter is replaced by placing the extension 33 in the prolongation 31 of the recess and then snapping the ears 40 or 40' into their receiving recess from the rear side of the blade.

The supporting portion 18 of the blade may be formed of an aluminum or other alloy such as now known, possessing a hardness and strength similar to steel by die-shaping or casting. By this method, close uniformity in the size and shape of the supporting portions 18 of the blades may be obtained, which would thus render the substitution or renewal of cutters 17 being made without difficulty. A uniform fit between the supporting part 18 and the cutter 17 used to replace other cutters is thus obtained.

The invention, it is to be understood, may receive other embodiments than those herein specifically illustrated and described, and may be applied to other types of scissors or shears than herein illustrated.

What I claim is:

1. A composite blade comprising a cutter and a supporting part and means for fastening said parts together, said cutter being a flat plate comprising resilient means at the rear edge thereof extending longitudinally with respect to the cutter, said means engaging over the rear edge of the supporting part.
2. A composite blade comprising a cutter and a supporting part and means for fastening said parts together, said cutter being a flat plate comprising a pair of oppositely disposed aligned tongues on the rear edge thereof engaging over the rear edge of the supporting part.
3. A composite blade comprising a cutter and a supporting part, and means for fastening said parts together comprising a groove in the rear edge of the supporting part and a tongue on the rear edge of the cutter adapted to be received in the groove from the rear side of the supporting part.

4. A composite blade comprising a cutter and a supporting part, and means for fastening said parts together, said cutter being a flat plate and said fastening means comprising oppositely disposed parts on the cutter at the rear edge thereof extending longitudinally with respect to the cutter and disposed in planes inclined to the planes of the faces of the cutter. 45
5. A composite blade comprising a cutter and a supporting part, and means for fastening said parts together, said cutter being a flat plate and said fastening means comprising a tongue and groove connection between said parts at the rear edges thereof, said tongue and groove extending longitudinally of the blade. 50
6. A composite blade comprising a cutter and a supporting part, and means for fastening said parts together, said cutter being a flat plate and said fastening means comprising a tongue and groove connection between said parts at the rear edges thereof, said tongue extending longitudinally with respect to the cutter and having its free end bent to incline it angularly with respect to the cutter. 55
7. A composite blade comprising a cutter and a supporting part, and means for fastening said parts together, said cutter being a flat plate and said fastening means comprising parts on the cutter at the rear edge thereof extending longitudinally with respect to the cutter disposed in planes inclined to the planes of the faces of the cutter, and a recess in the rear of said supporting part adapted to receive from the rear of said part the inclined parts on the cutter. 60
8. A composite blade comprising a cutter, and a supporting part, having a longitudinal recess on its inner face into which said cutter is adapted to fit, a shoulder on the supporting part at the rear of the recess for supporting said cutter opposite its cutting edge, a groove in said shoulder having a depth corresponding to the thickness of the cutter, a second groove in the rear of the supporting part communicating with the first groove and a tongue on the cutter adapted to fit in said grooves. 65
9. A composite blade comprising a cutter, and a supporting part having a longitudinal recess on its inner face into which said cutter is adapted to fit, a shoulder on the supporting part at the rear of the recess for supporting said cutter opposite its cutting edge, means for fastening said parts together comprising a tongue and groove connection near the outer end of the blade, said tongue being formed on the rear edge of the cutter and engaging in a groove in the rear of the supporting part, said tongue being resilient and adapted to co-act with the wall of said groove to urge the face of the cutter to lie flat within its recess. 70
10. A composite blade comprising a cutter, and a supporting part having a longitudinal recess on its inner face into which said cutter is adapted to fit, a shoulder on the supporting part at the rear of the recess for supporting said cutter opposite its cutting edge, means for fastening said parts together comprising a pair of oppositely disposed aligned tongues at the rear edge of the cutter near the outer end of the blade, said tongues having their free ends inclined to the planes of the faces of the cutter, and a groove in the rear edge of the supporting part near the outer end thereof, said groove being so disposed that when the tongues are inserted therein they are placed under a tension which tends to flatten the inclined portions thereof and urge the face of the cutter to lie flat within the recess in the supporting part. 75
- In witness whereof, I have hereunto signed my name. 80
